CLAIM

The ornamental design for a flexible cover for a sponge mop, as shown and described.

DESCRIPTION

FIG. 1 is a perspective view of a flexible cover for a sponge mop showing our new design, shown in its intended use with the broken line showing of a sponge mop being for illustrative purposes only and forming no part of the claimed design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a side elevational view thereof, the opposite side being a mirror image.

FIG. 1

FIG. 2

FIG. 3

FIG. 4

FIG. 5

FIG. 6
